UNITED STATES PATENT OFFICE.

OTTO HENRY HUEBEL, OF NEW YORK, N. Y.

DESIGN FOR A SPONGE AND SOAP HOLDER.

SPECIFICATION forming part of Design No. 29,620, dated November 8, 1898.

Application filed October 12, 1898; Serial No. 693,309. Term of patent 14 years.

To all whom it may concern:

Be it known that I, OTTO HENRY HUEBEL, a citizen of the United States, residing at New York, (Brooklyn,) Kings county, New York, have invented and produced a new and original Design for Sponge and Soap Holders, of which the following is a specification, reference being had to the accompanying drawing, forming part thereof, in which the figure is a perspective of the combined sponge and soap holder.

As shown in the drawing, the leading feature of my design consists of an oblong open frame within which depend two series of U-shaped arms, one series of arms being of greater depth than the other series and occupying a larger portion of the frame.

The open frame A has rounded corners and a cross-bar A' to one side of a line drawn transversely through the middle of its longitudinal bars a a. The deeper bars A² depend from the frame-bars a a, while the shorter

bars A³ depend from the cross-bar A' and the adjacent end bar a' of the frame A, except the two end bars of the series of bars A³, 25 which depend from the frame-bars a a in the direction of the length thereof.

The series of bars A³ constitute a receptacle for soap, while the series A² constitute a sponge-receptacle. The lower members of 30 the U-shaped arms A² A³ are straight, which gives a flattened appearance to the holder.

Suitable hangers or supports are provided, as shown in dotted lines.

What I claim is—

The design for a sponge and soap holder as shown and described.

In testimony whereof I affix my signature in presence of two witnesses.

OTTO HENRY HUEBEL.
